UNITED STATES PATENT OFFICE

2,452,630

TUBULAR FENCE POST CONSTRUCTION

Walter L. Burritt, Omaha, Nebr.

Application March 29, 1944, Serial No. 528,532

6 Claims. (Cl. 189—23)

1

The present invention relates to posts, more particularly fence posts employed for land enclosure purposes.

It is an object of the invention to provide a fence post construction which is of light weight, durable, strong and easily manufactured.

Another object of the invention is to provide an approximately hollow fence post which is so constructed that it is provided with a pointed end during manufacture thereof for facilitating an installation of the post in comparatively hard soils.

It is well known that the forests of the United States which heretofore have supplied conventional wood fence posts are becoming rapidly depleted. Also wood posts rot rapidly during use and often split when driven into hard soils, and the present invention aims to provide a post which is economical in construction for obviating the undesirable features attendant with the use of wooden posts, together with a provision of a post which, for installation in the softer soils, does not require a digging of post holes in the earth.

In the drawing, Figure 1 is a side elevation of a fence post embodying the present invention, a medial portion thereof being broken away and showing the post in a vertical position of use.

Figure 2 is a view similar to Figure 1 and showing the post turned at an angle of 90 degrees with respect to the showing thereof in Figure 1.

Figure 3 is an enlarged top plan view of the post.

Figure 4 is a transverse section of an upper portion of the post, the view being taken substantially on line 4—4 of Figure 3.

Figure 5 is an enlarged view of a portion of the post and showing a fence wire attached thereto.

Figure 6 is a plan view of a fence wire attaching device preferably employed in conjunction with the new post structure.

In the drawing, 10 generally indicates the fence post of the present invention. Structurally the new post is tubular in plan as shown in Figure 3, being formed of a homogeneous elongated sheet of metal having a main body portion 11.

A rib 12 is disposed outstandingly and longitudinally with respect to said main body portion, as shown in Figure 1. Preferably the rib extends the entire length of the main body portion of the post.

As best shown in Figure 2, the rib 12 is preferably provided by crimping the sheet of metal adjacent the longitudinal edge 13 thereof in a manner whereby the rib outstands from said sheet

2

at approximately a right angle and by bending the sheet upon itself for said purpose.

The rib 12 is provided with a plurality of apertures 14 which are equi-distantly spaced apart a few inches with respect to each other and disposed in a row, as best shown in Figure 1, for the purpose of receiving the later described fence wire fastening element shown in Figure 6. The other longitudinal edge 15, together with the edge 13, are welded or otherwise suitably secured, to the main body portion 11 of the post and preferably a transversely disposed brace 16 is employed. The brace is preferably welded to the main body portion of the post as indicated at X.

15 The sheet metal is provided with a plurality of indentations 17 for stiffening and reinforcing purposes, only two of said indentations being depicted for convenience of illustration, said indentations stiffening the comparatively thin sheet metal. In practice, the sheet of metal may be of 24 gauge and preferably the post is galvanized for rust proofing purposes.

20 The lower end of the post is incised and cut away for providing a comparatively sharp pointed end 18 for facilitating driving the post into the soil. The cut-away portion provides a bottom edge 19 which is disposed at an angle of approximately 45 degrees with respect to the length of the post and for driving the latter into hard soil such as clay or the like, a more acute angle may be provided for said bottom edge.

25 The upper edge 20 of the post is covered with a jig, not shown, which fits snugly against the inner wall and the outer annular wall of the post for facilitating a driving of the latter into the soil 21 in a vertical direction.

30 Referring to Figure 6, 22 indicates generally the fence wire fastening element of the present invention.

35 The device 22 is formed of a single piece of wire of suitable length, having a main body portion 23. Approximately midway between the ends of the main body portion 23, the latter is provided with a coil 24. The coil provides an aperture 25 for receiving a fence wire 26 therethrough. At times when the wire 26 is barbed and provided with outstanding tangs, not shown, the coil 24 is provided not closed upon itself as shown in Figure 5 for facilitating either drawing the barbed wire through the aperture 25 or placing the coil 24 about the wire.

40 In operation, a line of fence posts are erected by driving their pointed ends into the soil and in order to attach the wire 26 to the posts, the wire is drawn through the aperture 25 of the

member 22 and at this time, the ends 27 and 28 are disposed at a right angle with respect to the main body portion 23 of the device 22 as shown in Figure 6.

The ends 27 and 28 are spaced apart a distance with respect to each other complementary to the distance between the apertures 14 of the rib 12, whereby the ends 27 and 28 may be inserted through respective apertures 14 of the rib and bent upwardly as at A and downwardly as at B respectively, as shown in Figure 5, for attaching the wire 26 to the post.

In order to provide a good installation, preferably an anvil is held against the points C of the element 22 and the operator strikes the portions D with a hammer for swaging the element 22 for fastening it securely to the post and in instances where the coils 24 are loose, pliers or the like are employed for causing the opposite sides of the coil to be closed towards each other, as shown in Figure 5.

The manner of manufacturing the posts of the present invention embraces providing an elongated, comparatively thin sheet of metal. The first part of the operation is to place the sheet upon a female die, the latter being under a power press mechanism having a male die carried thereby. The male die upon its descent causes the indentation 17 to be provided in instances where said indentations are employed. During the descent of the male die, the latter incises the sheet metal to provide the inclined lower edge 20 of the post at the time the latter is rolled as later described. During the descent of said die, the apertures 14 are simultaneously punched through the sheet of metal.

The next step of the method is to crimp the sheet adjacent one of the longitudinal edges thereof to provide the rib 12 and in a manner whereby the oppositely disposed holes for receiving the wire fastening element 23 are properly aligned.

The sheet of metal is now bent upon itself longitudinally to provide the brace 16 the latter, at the time, being disposed at a right angle with respect to the main body portion of the sheet. If desired, adjacent the edge 15 of the sheet and in alignment with said edge, the sheet is further processed to provide a flange 29, the latter being disposed at a right angle with respect to the brace 16 and in approximate parallelism with the main body portion of the then flat sheet.

After the steps as above described have been consummated, the sheet is then rolled upon itself to dispose the edge 15 inwardly of the sleeve thus provided and the edge 13 outwardly of said sleeve with the brace 16 transversely disposed, as shown in Figure 3. The edges 13 and 15 are now welded or otherwise suitably secured to the main body portion of the post thus provided.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

I claim:

1. A sheet-metal post formed of a single sheet of metal rolled into a configuration having a generally tubular portion and a bracing portion, said sheet being elongated and one longitudinal edge of said sheet being disposed overlapping

the outer side of said tubular portion, the other longitudinal edge of said sheet being disposed against the inner side of said tubular portion, a longitudinal section of said tubular portion being folded longitudinally so that the two parts of said longitudinal section are disposed in approximate parallelism with respect to each other, said two parts having spaced apertures therethrough, the apertures of one of said parts being in alignment with the apertures in the other of said parts.

2. A sheet-metal post formed of a single sheet of metal rolled into a configuration having a generally tubular portion and a bracing portion, said sheet being elongated and one longitudinal edge of said sheet being disposed overlapping the outer side of said tubular portion, the other longitudinal edge of said sheet being disposed against the inner side of said tubular portion, a longitudinal section of said tubular portion being folded longitudinally so that the two parts of said longitudinal section are disposed in approximate parallelism with respect to each other, said two parts having spaced apertures therethrough, the apertures of one of said parts being in alignment with the apertures in the other of said parts, that longitudinal edge of that one of said parts which is disposed farthest from said first mentioned longitudinal edge being rigidly secured to said bracing portion at the junction between said tubular portion and said bracing portion.

3. A sheet-metal post formed of a single sheet of metal rolled into a configuration having a generally tubular portion and a bracing portion, said sheet being elongated and one longitudinal edge of said sheet being disposed overlapping and secured to the outer side of said tubular portion, the other longitudinal edge of said sheet being disposed against the inner side of and secured to said tubular portion, a longitudinal section of said tubular portion being folded longitudinally so that the two parts of said longitudinal section are disposed in approximate parallelism with respect to each other, said two parts having spaced apertures therethrough, the apertures of one of said parts being in alignment with the apertures in the other of said parts.

4. A post as described in claim 1 in which said second mentioned longitudinal edge of said sheet is rigidly secured to the inner side of said tubular portion.

5. A post as described in claim 1 in which said second mentioned longitudinal edge of said sheet overlaps the tubular portion thereof at a point approximately diametrically opposite said first mentioned longitudinal edge across said tubular portion.

6. A sheet-metal post formed of a single sheet of metal rolled into a tubular configuration, one longitudinal edge of said sheet being disposed overlapping the outer side of a longitudinal section of the sheet, which section is disposed between the longitudinal edges of the sheet, a second longitudinal section of said sheet being folded longitudinally so that two parts of said longitudinal section are disposed in approximate parallelism with respect to each other, said two parts having spaced apertures therethrough, each of the apertures of one of said parts being in alignment with one of the apertures in the other of said parts.
